UNITED STATES PATENT OFFICE

ALFRED PEYTON WILLIAMS, OF MADISONVILLE, KENTUCKY

TOY ELECTRICALLY-OPERATED SHOVEL

Application filed January 24, 1929. Serial No. 334,754.

This invention relates to metal toys and particularly to a toy having the form of a miniature steam or electric shovel and the general object of the invention is to provide a toy 5 of this character which is amusing, entertaining and educational and which simulates very accurately the action of an electrically operated shovel or of a steam shovel under actual working conditions, or in other words, 10 to provide a toy of this kind having a scoop or dipper and mechanism whereby the load may be picked up, elevated, the supporting frame rotated to the right or left under power, and the load dumped either to the right or left 15 within the range of the machine.

A further object is to provide a toy of this character having three separate and independent electric motors, one motor controlling the forward and rearward movement of 20 the scoop, another motor controlling the vertical movement of the scoop, and third motor controlling the revolution of the boom and house upon the truck.

Other objects will appear in the course of 25 the following description.

My invention is illustrated in the accompanying drawings, wherein:—

Figure 1 is a side elevation of a toy electric shovel constructed in accordance with my 30 invention;

Figure 2 is a fragmentary rear elevation of the upper portion of the house showing the electric switches;

Figure 3 is a top plan view of the rotatable 35 platform;

Figure 4 is a sectional view through the rotatable platform taken across the center of rotation thereof;

Figure 5 is a fragmentary top plan view of 40 the scoop or dipper supporting arms and the actuating mechanism therefor;

Figure 6 is a fragmentary section through the scoop supporting arms and through the scoop;

Figure 7 is an enlarged elevation partly in section of the boom, the scoop supporting arms and the actuating mechanism therefor;

Figure 8 is a sectional view through the shaft supporting the pinion for actuating 50 said arms and showing an elevation of the

arm and yoke for holding the arms in engagement with the pinion;

Figure 9 is an enlarged sectional view through the tubular bolt and a portion of the platform mounted thereon;

Figure 10 is an enlarged sectional view of the shovel on the same lines as Figure 6 but showing the bottom of the shovel released and in a discharging position.

Referring to the drawings, 10 designates a truck having wheels 11, which truck may be of any suitable construction. 12 designates a platform having a house or cover 13 supported by the uprights 14. This house may be of any suitable or approved construction. The 60 platform 12 is rotatably mounted as shown in Figure 4 for movement around a central bolt 15 which extends upward through the truck. The truck as shown in Figure 4 supports a fixed table or raceway 16. The platform 12 is provided with a raceway 17 and between these raceways are disposed anti-friction balls 18 supported in a freely rotatable carrier 19 in an obvious manner. The bolt 15 at its upper end passes through the platform 12 and 65 is held in place by the nuts 20 and at its lower end passes through a horizontal plate 21 and is provided with nuts 22. This bolt is tubular and at its upper end carries the collector rings 70 or commutator rings 23 and 24 as shown in Figure 9. The conductor 25 which leads from a source of electricity extends upward through the bolt 15 and at its upper end, the wires of the conductor are bared, one of these 75 wires extending to the collector ring 23 and the other to the collector ring 24. By this means current is supplied to the several 80 motors as will be later stated.

The table or raceway 16 is formed by a fixed gear wheel, the teeth of which engage 85 a pinion 26 mounted upon the lower end of the shaft extending upward through a tubular post or support 27, see Figure 1, this shaft carrying at its upper end the gear wheel 28.

This gear wheel 28 is engaged by a worm 90 29 mounted upon a horizontal shaft 30 supported in bearings, this shaft in turn carrying a gear wheel 31 engaged by the pinion 32 mounted upon the shaft of an electric motor 33. Energizing this motor the platform 12 95

100 said arms and showing an elevation of the

may be rotated to any desired extent in either direction, the motor being reversible.

Mounted upon the platform 12 and extending upward and outward therefrom is a boom 34 carrying at its upper end, the grooved wheel or pulley 35. The outer end of this boom is supported by means of the brace rods 36. Mounted upon the boom intermediate its length is a shaft 37, carrying upon it the worm wheel 38. This shaft at its outer end is supported in bearings 39 and the extreme outer end of the shaft supports the yokes 40 having upwardly diverging arms carrying the rollers 41. The shaft 37 between the arms of the yokes carries upon it the pinions 42. Passing over these pinions are the racks 43 which constitute the supporting arms for the shovel or scoop 44. These arms 43 have rack teeth on their under faces engaging with the pinions 42. As the shaft 37 is rotated in one direction or the other the racks 43 are forced outward or retracted.

For the purpose of rotating the gear wheel 38 I provide the worm 45 carried by the shaft 46 which shaft extends downward approximately parallel to the boom 34 and is supported in a bearing 47 in turn supported upon the boom.

The shaft 46 at its lower end is connected with the shaft of an electric motor 48 capable of operating in either direction and it will be seen that as this motor is operated the shaft 37 will be turned in one or the other direction and that thus the arms 43 which support the scoop 44 will be either projected or retracted.

The scoop 44 as shown best in Figure 10, is rigidly connected to the extremities of the arms 43. The scoop is open at its upper and lower ends and pivoted to the side walls of the scoop are the angular arms 49 which support the scoop bottom 50. This bottom is normally closed as shown in Figure 6 and is held in this closed position by means of a latch 51. This is carried on arms which extend rearward and are connected to a rock shaft 52, see Figure 5. A spring 53 engages the latch 51 and urges it upward to a position where the extremity of the latch will engage with a notch 54 formed on the arms 49. This spring 53 at its upper end is supported by means of a transverse plate 55 and pivotally mounted upon this plate is a lever 56 which is angular in form and one end of this lever is slotted at 57 and is engaged with a pin 58 projecting radially from the shaft 52.

As the outer end of this lever is shifted rearward, the pin 58 will be rocked forward and the latch 51 withdrawn from its engagement with the notch 54, permitting the bottom of the scoop to drop to the position shown in Figure 10. When the scoop has been turned to an operating position, the bottom 50 will close by gravity and the latch 51 will spring into place in engagement with the

notch 54, thus once again holding the scoop with the bottom closed.

Attached to the rear wall of the scoop is pulley 59 and extending through this pulley is a cable 60, one end of which is operatively connected to the boom 34 as for instance at the point of connection with the stays 36, this cable after it passes through the pulley 59 extending over the grooved wheel 35 and extending downward to a drum 61 mounted in suitable bearings upon the platform 12. This drum at one end is provided with the gear wheel 62 meshing with a pinion 63 on a shaft 64 which carries a gear wheel 65 in turn meshing with a gear wheel 66 on the shaft 67 of an electric motor 68. Thus by actuating this motor in one or the other directions, the cable will be wound in or paid out to raise or lower the scoop.

The electric current is conducted to the several motors 33, 48 and 68 by brushes 69 engaging the rings 23 and 24, conducting wires leading from these brushes to the switch box 70 and the current being directed to the several motors so as to rotate the motors in either direction by means of the conventional switches 71. I have not illustrated any particular wiring system whereby this may be achieved but this will be obvious to any electrician. The three switches 71 are independently operable to throw the current on or off of each one of the motors independently of the other motors and to cause the rotation of the motors in either direction. Thus by operating one of the switches, it will be obvious that the platform with the boom 34 may be swung around in a horizontal plane. By operating the motor 68, the scoop may be raised or lowered and by operating the motor 48 in one or the other direction, the scoop may be crowded outward or retracted.

The rollers 41 hold the arms 43 engaged with the pinions 42 in any position of the arms 43 whether these arms are in a horizontal position, slanted upward and rearward or slanted downward and rearward. It will be understood, of course, that the yokes 40 are so mounted upon the shaft 37 that they may swing around the shafts upon a center to permit the movement of the arms 43 in a plurality of inclined positions. The arm 56 is intended to be connected to an operating cord extending backward to a position adjacent the switches so that a child operating the device may dump the scoop at any desired point.

Preferably the gear wheels 28 and 65 will be connected to these shafts by means of a wooden drift pin 72 and such wooden drift pins are used to fasten the spur gears to the shafts on which they are fitted, thus providing means to relieve strain when moving parts become locked for any reason, these pins shearing under this strain.

All of the parts may be made of thin metal except the wheels, and the boom 34 is of

pressed metal, channel-shaped or rectangular in cross section. The platform and the cabin may be made of light metal formed up and secured together in any suitable manner. It will be seen that there are no clutches in this construction which require that the several instrumentalities shall be operated from one motor, but that the several instrumentalities necessary to operate the scoop and shift it outward or inward, raise or lower it or carry it or swing it in a horizontal plane are each operated by a separate motor. This renders the device much more simple than where a single motor is used and makes the control of the several motors of such simple character that the device is readily understood by any child.

This device may be readily operated by any child. Thus all motors may be operated separately or in unison and either forward or backward as desired by the operator. The electric current may be obtained from a lighting system.

While I have illustrated wheels 11 upon the motor truck, it will be understood that an endless track might be used and that the wheels and track might be power driven by means of an electric motor on the truck or platform.

I claim:

In a toy power shovel the combination of a boom, a scoop, a pair of arms mounted upon the scoop and extending transversely of the boom, means on the boom for shifting the arms outward or inward, means on the boom for raising or lowering the scoop, angular arms pivoted upon the scoop and carrying a scoop bottom, the angular arms having notches, a latch pivoted upon the first named arms and adapted to engage with the notches in the bottom supporting arms, a spring mounted on the arm and engaging said latch for urging the latch into latching position, a shaft upon which the latch is mounted and having a radial arm, and a lever having a slot in which said radial arm is disposed, the lever being shiftable to release the latch.

In testimony whereof I hereunto affix my signature.

ALFRED PEYTON WILLIAMS.
